Primary Examiner — Selina Sikder(74) *Attorney, Agent, or Firm* — Syncoda LLC; Feng Ma(57) **CLAIM**

The ornamental design for a controller for lights, as shown and described.

DESCRIPTION

The patent or application file contains a least one drawing executed in color. Copies of this patent or patent application publication with color drawing(s) will be provided by the Office upon request and payment of the necessary fee.

FIG. 1 is a front view of a controller for lights showing my new design;

FIG. 2 is a front-right side perspective view thereof;

FIG. 3 is a front-bottom side perspective view thereof;

FIG. 4 is front-left side perspective view thereof; and,

FIG. 5 is a back-top side perspective view thereof.

The broken lines in the drawing depict a portion of the controller for lights that form no part of the claimed design.

1 Claim, 5 Drawing Sheets
